DIESTOCK

Harry O. Olsen, New York, N. Y.

Application June 1, 1944, Serial No. 538,275

4 Claims. (Cl. 10—124)

The present invention relates to die stocks. One of its objects is to provide a die stock which is not subject to torsional twisting during use.

Another object is the provision of a die stock whose axial dimensions are smaller than those of conventional die stocks.

A further object is the provision of a die stock whose component parts are fewer in number than the parts of conventional die stocks.

These and other objects are attained by providing a ring shaped body member carrying a pawl and a handle lever radially disposed thereto, a ratchet wheel rotatably mounted wholly within the confines of said body member, a die member fixedly mounted wholly within the confines of said ratchet wheel, and a guide ring fixedly mounted at least in part within the confines of said ratchet wheel. Other features of the invention will hereinafter be described.

Preferred embodiments of the invention are shown in the accompanying drawing in which:

Figure 1 is a plan view of one embodiment of the device with a cut-away portion exposing the operative elements of the ratchet member thereof;

Figure 2 is a section on the line 2—2 of Figure 1;

Figure 3 is a plan view of a second embodiment of the device;

Figure 4 is a plan view of a third embodiment of the device with a cut-away portion exposing the operative elements of the ratchet member thereof;

Figure 5 is a section on the line 5—5 of Figure 4;

Figure 6 is a similar view of the die member thereof; and

Figure 7 is a plan view of said die member.

Referring to the embodiment shown in Figures 1 and 2, the die stock 10 comprises a combination die-guide-ratchet wheel member 11 rotatably mounted within a pawl carrying ring 12 which has a handle receiving aperture 13 formed therein. Said die and ratchet wheel members are mounted wholly within said ring and the guide member at least partly within said ring.

The combination member 11 consists of a die 20 and a guide ring 21 mounted in a ratchet wheel 22, all of said parts being in axial alignment with each other, said die member being mounted wholly within the confines of said ratchet wheel, said guide ring partly within said confines. Combination member 11 may be made of a single piece of metal or of separate die, guide

and ratchet wheel units affixed to one another by a metallic bond as by sweating. Of course chaser dies 19 are affixed in die member 20 in the usual way and are made of different, tougher material. Axial movement of combination member 11 relative to said pawl carrying ring 12 is prevented by peripheral flanges or ridges 18 which are integral with or affixed to the two sides of ratchet wheel 22.

10 The pawl carrying ring 12 is conventional and comprises a ring whose inner diameter is slightly larger than the outer diameter of combination member 11 thus enabling the latter to fit snugly, yet rotatably, in the former. The ring has two radial apertures 13 and 25 formed therein, said apertures being diametrically opposite each other. The function of aperture 13 is to receive the handle (not shown). Integral with ring 12 or affixed thereto, is outwardly projecting, radially disposed, 15 apertured barrel 26, said barrel being in axial alignment with aperture 25. The aperture 27 in said barrel has a reduced portion at its far end, thus forming an inner, circumferential shoulder 28. Turnably and slidably disposed in said aperture 27 is the pawl 29, said pawl comprising an enlarged, lower, operational end 30, an upper reduced stem portion 31 affixed thereto or integral therewith, said stem portion projecting outwardly beyond said barrel, a knob 32 affixed to the outer, projecting end of said stem portion, a helical torsion spring 33 mounted on said stem portion between and against said lower, operational end 30 and said barrel shoulder 28, and 20 a cross-pin 34 transversely fixed in the upper portion of said stem portion, in spaced relation with respect to said knob, said pin being adapted, in response to the action of said spring, to enter radial slots 35 formed in the far end of said barrel.

40 Pawl carrying ring 12 has its identical counterpart 40 in the embodiment shown in Figure 3. In this embodiment, however, die member 41 and ratchet wheel 42 in which it is wholly mounted, 45 are separate units, relative rotational movement between the two being prevented by means of outwardly projecting lug portions 43 of chaser dies 44 which extend beyond the outer peripheral surface of said die member, and project into correspondingly shaped and positioned grooves 45 formed in the inner peripheral surface of said ratchet wheel.

50 In this embodiment the guide ring may either be integral with or affixed to the ratchet wheel or integral with or affixed to the die member. Here

too the guide member is situated at least in part within the confines of said ratchet wheel.

In the embodiment shown in Figures 4 to 7 inclusive, the pawl carrying ring 50 which is the counterpart of pawl carrying ring 12 has a slightly different structure as hereinafter described. It has two handle receiving apertures 51 instead of one, and its pawl carrying barrel 52 which is the counterpart of barrel 26, is axially aligned with neither of said apertures. In this embodiment the apertures are formed diametrically opposite each other, the barrel 52 being positioned adjacent one of said apertures. Said ring has internal screw threads 53 at one edge and two flanges—an inner, radial flange 54 and an outer, lateral flange 55—formed at the other edge. A washer or ring 56 having peripheral screw threads is screwed into pawl carrying ring 50 at its threaded side.

An inner circumferential channel is thus formed, the inner surface of the pawl carrying ring 50, the radial flange 54 and the washer 56 constituting its three walls. It is in this channel that ratchet wheel 60 is rotatably mounted. In this embodiment, as in the embodiment shown in Figure 3, the die member 61 and the guide ring 62 form a unitary structure separate from ratchet wheel 60. As can be seen in the drawing, particularly Figures 4 and 7 thereof, the die member 61 is polyhedral—in this case octahedral—in shape, instead of circular or cylindrical as in the case with die member 41. The inner surface of the ratchet wheel 60 corresponds in shape to octahedrally shaped die member 61, so that each of the individual plane surfaces of the latter has its corresponding plane surface on the inside of the ratchet wheel, the plane surfaces of the die member being parallel, respectively, to the plane surfaces of the ratchet wheel. It is this polyhedral arrangement that prevents rotary movement of these parts relative to each other.

As can be seen in Figures 5 and 6, the peripheral portion 63 of guide ring 62 abuts the adjacent sides of radial flange 54 and lateral flange 55. A groove 64 is formed in said peripheral portion, said groove being adapted to receive a tongue or pin 65 which is radially and slidably mounted in lateral flange 55. Said pin is affixed to a leaf spring 66 which in turn is fixed to lateral flange 55. To disengage the pin from the groove it is only necessary to raise the pin end of the spring with the finger. This pin-in-groove construction prevents axial movement of the die-guide ring unit, relative to the pawl carrying ring 50, as well as to the ratchet wheel 60.

Figure 4 shows how handle lever 70 is inserted into one of the two handle receiving apertures 51.

It is evident that the broad principles of the invention cover a multitude of embodiments not herein shown. For example washer or ring 56 might be affixed to pawl carrying ring 50 by means of bolts, screws or rivets instead of the external screw threads with which it is equipped. Such changes are herein contemplated and claimed.

I claim:

1. A die stock comprising a ring shaped body member, a pawl and a handle lever carried by said body member in radial relation thereto, a ratchet wheel rotatably mounted wholly within said body member, a die member fixedly mounted wholly within said ratchet wheel, and a guide ring fixedly mounted at least in part within said ratchet wheel, said body member, ratchet wheel, die member and guide ring being in coaxial relationship with each other.

2. A die stock comprising a ring shaped body member, a pawl and a handle lever carried by said body member in radial relation thereto, a ratchet wheel rotatably mounted wholly within said body member, said ratchet wheel being engaged by said pawl, said ratchet wheel having a pair of peripheral flanges affixed to the sides thereof to prevent axial movement thereof relative to said body member, a die member mounted wholly within said ratchet wheel, a guide ring mounted at least in part within said ratchet wheel, said ratchet wheel, die member and guide ring being affixed to each other by a metallic bond, said body member, ratchet wheel, die member and guide ring being in coaxial relationship with each other.

3. A die stock as claimed in claim 1 in which the ratchet wheel has lug receiving apertures formed in its inner circumferential surface and the die member carries lugs on its outer circumferential surface, said lugs being integral with chaser dies carried by said die member, said lugs being adapted to project into said apertures to prevent relative movement between said ratchet wheel and said die member.

4. A die stock as claimed in claim 1 in which the die member is polyhedrally shaped and the inner surface of the ratchet wheel is correspondingly shaped to prevent relative rotary movement between said die member and said ratchet wheel.

HARRY O. OLSEN.
